UNITED STATES PATENT OFFICE.

ANTHONY CONTI, OF PITTSFIELD, MASSACHUSETTS.

LETTERING DEVICE.

Application filed January 7, 1926. Serial No. 79,901.

My invention relates to a lettering device in which a series of letters and numerals may be marked out on a disk, and the method of using the letters and numerals be controlled 5 from a central point.

Another object of my device is to provide a lettering device that is controlled from a central point, from which point radiates a series of letters and numerals of various 10 sizes and designs.

Another object of my device is to provide a scale in conjunction with a lettering device to facilitate the means for spacing the letters and numerals used with the lettering device.

15 Other objects and advantages of the invention will be fully understood from the following description and claims when taken in connection with the accompanying drawings, forming part of this specification in 20 which:

Figure 1 is an elevation side view.

Figure 2 is a plan view.

Referring to the drawings by numerals, 1 designates a circular disk, which disk is supported by the side arms 2. The side arms 2 terminate in a cross arm 15, which cross arm acts as an additional support for the circular disk. The circular disk 1 is rotatably connected to the cross arm 15 by means of the 25 bolt 16 and the nut 3. The lower ends of the side arms 2 are connected together by the straight edge 5. The straight edge 5 is provided with a recess 18, indented thereon thruout the entire length of the said straight 30 edge, so as to bring it in alignment in a horizontal plane with the cross arm 15, so that the device will set level with the straight edge 5 and the cross arm 15 bearing against the surface on which the letters or numerals 35 are to be outlined when the lettering device is placed in the position as shown on the plan view as indicated in Figure 2. The straight edge 5 is turned over on the end as indicated by the numeral 17, this being done so to 40 facilitate the straight edge 17 being used with another straight edge. The straight edge 5 is also provided with a graduated scale 4 to provide means to assist in spacing the distance between the letters and numerals 45 as they are outlined from the disk 1.

A series of lines 7 radiate from a central point on the circular disk 1, which disk in this particular case is divided into four separate circular spaces, and these radial lines designate the position of the letter or numeral on the disk. It will be seen by referring to the

drawing that the circular disk may be divided into any number of separate circular spaces, therefore, I do not wish to limit myself to four circular spaces as shown on the 60 drawing. It will also be seen that by using a circular disk and spacing the letters and numerals by radial means I am able to obtain a series of letters and numerals of various 65 sizes.

The letters and numerals are stamped out of the disk, and it will be seen from the drawing that the second letter "B" of the alphabet I obtain by joining the letters indicated on the drawings by the numerals 8 70 and 9. The letter "O" as indicated by the numeral 12 also acts as the figure 0. The numeral 13 indicates that part which is necessary to complete the letter "Q" and is used in connection with the letter "O." The numeral 14 indicates that part which is necessary to use with the letter "P" to complete the letter "R." The numerals 10 and 11 indicate the parts on the disk that are used together to form the numeral "8." 80

The device is operated as follows:

When it is desired to print any particular letter or numeral that letter or numeral on the radial line 7 is brought in line with the arrow 6 on the graduated scale 4. When in this position a sharp pointed lettering pen is inserted in the letter or numeral to be printed and by drawing the pen point about the contour of the letter or numeral it can be readily printed. Any desired space between the letters or numerals can be regulated by means of the graduated scale 4. 90

Having thus described my invention, what I claim as new and desire to secure by Letters Patent, is:

1. In a lettering device of the class described comprising a disk provided with a series of punched letters and numerals, side arms terminating in a cross arm, means to rotatably connect the disk to the said cross arm, a graduated straight edge connected to the side arms, said graduated straight edge being provided with means for spacing the distance between the letters and numerals as they are outlined from the disk. 100

2. In a lettering device of the class described comprising a disk provided with a series of letters and numerals of various sizes punched on radial lines on said disk, side arms terminating in a cross arm, means to rotatably connect the disk to the said cross arm, a graduated straight edge connected to 110

- the side arms, said graduated straight edge provided with a recess indented thereon, said recess to provide means to bring the said graduated straight edge in alignment in a horizontal plane with the said cross arm, said graduated straight edge being provided with means for spacing the distance between the letters and numerals as they are outlined from the disk.
3. In a lettering device of the class described comprising a disk provided with a plurality of circular spaces, said circular spaces provided with a series of letters and numerals of various sizes punched through the disk in said spaces, side arms terminat-
- ing in a cross arm, means to rotatably connect the disk to the said cross arm, a graduated straight edge connected to the side arms, said graduated straight edge provided with a recess indented thereon, said recess to provide means to bring the said graduated straight edge in alignment in a horizontal plane with the said cross arm, said graduated straight edge being provided with means for spacing the distance between the letters and numerals as they are outlined from the disk. 20 25

In testimony whereof I affix my signature.

ANTHONY CONTI.
